UNITED STATES PATENT OFFICE.

FRIDOLF FRANKEL, OF STOCKHOLM, SWEDEN.

MEANS FOR STRETCHING A RESONANT PLATE OVER A FRAME.

1,078,424.

Specification of Letters Patent.

Patented Nov. 11, 1913.

Application filed July 18, 1912. Serial No. 710,298.

To all whom it may concern:

Be it known that I, FRIDOLF FRANKEL, a subject of the King of Sweden, residing at Stockholm, in the Kingdom of Sweden, have 5 invented new and useful Improvements in Means for Stretching a Resonant Plate over a Frame, of which the following is a specification, reference being had to the drawing accompanying and forming a part 10 hereof.

My invention relates to improvements in means for stretching a resonant plate over a frame for instance in pianos or other string instruments, especially such a plate as 15 is constructed from sheet metal.

The main object of my invention is to provide means for stretching the plate in a most uniform manner, and, if so desired, with stronger tension in the treble, or the 20 part of the plate intended for the highest tones. To gain this object I fasten a plurality of stretching levers to the edges of the plate, and provide means for attaching the stretching levers to the frame and also 25 means for adjusting the position of the stretching levers relatively to the frame. Whether the said stretching levers should be attached first to the plate or to the frame depends partly on the form of the stretching 30 levers and partly on other circumstances such as the available space, and so forth. The stretching levers are provided with means, such as hooks or screws, for attaching them to the frame, and with other 35 means, as wedges or screws, for stretching the plate or for putting tension upon the same.

My invention is illustrated in the accompanying drawing, in which—
40 Figures 1 to 4 show in sectional views several ways of applying the invention to the plate and frame of a piano. Fig. 5 illustrates the arrangement shown in Fig. 4 in a view at right angles to said figure.

45 Referring to the drawings, 2 represents the resonant plate, made of sheet metal, and provided along its edges with lugs or tongues 3, which by means of screws 4, or

by soldering, are securely fastened to stretching levers 5. These are attached all 50 around to the frame 1, with a suitable distance between the different stretching levers.

In Fig. 1 the stretching lever is formed with a hook 6, arranged to engage the edge 7 formed in the frame 1. The stretching of 55 the plate is done by means of the set-screws 8 which are threaded through the stretching lever and rest with their ends in a groove in the frame 1. If desired more than one of such setscrews 8 can be used in each 60 stretching lever.

In the modifications shown in Figs. 2 and 3 the hook 6 is substituted by a screw 9 passing through the stretching lever and threaded through the edge of the frame 1. This screw serves as an adjustable support for the stretching lever and at the same time 65 as a means for stretching the plate. The stretching can also be done by the setscrew 8 threaded through the frame 1 and arranged to press outward the upper part of 70 the stretching lever. In Fig. 3 a wedge 10 is used instead of the aforesaid setscrew 8.

In Figs. 4 and 5 the stretching lever is fulcrumed on an edge 11 formed upon the 75 outside of the frame 1, and the stretching of the plate is done by tightening the nut 12 of the screw-bolt 13, which passes freely through a hole in the frame.

The above described means for stretching 80 the resonant plate possesses also the advantage that there are no parts extending far beyond the edge of the plate, which advantage is quite important in the manufacture of grand pianos.

85 What I claim is:

1. The combination of a resonant plate, a frame, a plurality of stretching levers fastened to the edges of the plate, means for attaching the stretching levers movably 90 to the frame, and means for moving the stretching levers so as to stretch the plate.

2. The combination of a resonant plate, a frame, stretching levers fastened to the edges of the plate and fulcrumed on the 95 frame, said resonant plate being fastened

to the stretching levers, and means for moving the stretching levers so as to stretch the plate.

3. The combination of a resonant plate, a frame provided with an edge, stretching levers fastened to the edges of the plate and fulcrumed on the edge of the frame, said resonant plate being fastened to the stretch-

ing levers, and a screw passing through each stretching lever and the frame adapted to move the stretching lever so as to stretch the plate.

FRIDOLF FRANKEL.

Witnesses:

FREDR. NORDSJÓ,
O. M. SANDELL.
